UNITED STATES PATENT OFFICE.

JOHN A. COOK, OF BUFFALO, NEW YORK.

PAGE-INDEX.

SPECIFICATION forming part of Letters Patent No. 400,059, dated March 26, 1889.

Application filed September 5, 1887. Serial No. 248,843. (No model.)

To all whom it may concern:

Be it known that I, JOHN A. COOK, of Buffalo, in the county of Erie and State of New York, have invented certain new and useful 5
5 Improvements on a Page-Index; and I do hereby declare that the following description of my said invention, taken in connection with the accompanying sheet of drawings, forms a full, clear, and exact specification, which will 10
10 enable others skilled in the art to which it appertains to make and use the same.

My present invention has general reference to page-indexes for books of all kinds, especially for ledgers and other books used in 15
15 book-keeping, works of reference, &c., where frequent reference to pages is made; and it consists, essentially, in the peculiar arrangement, as hereinafter first fully set forth and described, and then pointed out in the claims. 20
20 In the drawings heretofore mentioned, forming a part of this specification, Figure 1 is a perspective view of a book provided with my page-index. Figs. 2 and 3 are plan views of the same.

25 Like parts are designated by corresponding letters of reference in all the figures.

The object of my present invention is the production of a page-index for books, whereby all the page-numbers of a book, pamphlet, &c., 30
30 may be seen at a glance, and the page desired to be opened immediately and unerringly found. To accomplish this object I arrange all the page-numbers of a book, A, on the side of the same, substantially as now an ordinary 35
35 alphabetical index is arranged, except that in books having a large number of pages, which do not allow of having them all placed in one row, I arrange them in a series of rows, substantially as shown in the figures, the rows to 40
40 be either on one side (or edge) or on both sides of the book. I prefer, however, to construct the same by arranging the index on both edges of the book, as shown in Fig. 1, where the index B is in full view when the 45
45 book is opened in the middle. In this case I arrange all the even numbers on the edge of the first or left half of the book and all the odd numbers on the right half of the same. In this position the numbers will be on the 50
50 proper side of the pages.

In indexing I begin with the lowest number

on the lowest part of the first row and arrange as many rows as are necessary to place all the even numbers of one-half of the book onto the left-hand side, so that the highest even 55 number is on the top of the index of that side. I then index the opposite side of the book in the reverse way, beginning with the first odd number in the middle of the book on the top of the first right-hand page and 60 ending with the highest odd number on the bottom of the index on the right-hand side, so that if I wish to open any page the number of which is less than one-half of all the pages I use the left-hand index, while if said 65 page-number is greater than the middle number I use the right-hand index.

It is true the index on both sides of the book registers the first half of all the even and the second half of all the odd numbers 70
70 only. This, however, is no objection, because if any odd number in the first half of the book is desired to be opened it is only necessary to open the even number next and immediately preceding the odd number required. For instance, assuming page 15 is required to be opened, by placing the finger or thumb onto the figure 14 and opening the book, page 15 will also be found opened, while, if, say, page 56 is required, the thumb 80
80 of the right hand should be placed upon the immediately preceding higher odd number 57, and the book opened, when said page 56 will be opened and found on the leftside. It will now be readily seen that by means of this 85
85 index containing all the page-numbers of a book any page can be immediately found and opened without the slightest mistake and without turning a single page but exactly the one required. 90
90

In posting ledger accounts this index is one of the most labor-saving devices now in use, and since this indexing adds but a very trifle to the cost of production of a book it will find ready sale with the trade. 95
95

It will be readily observed that a book needs no other paging but that of the index, which would be sufficient for all practical purposes, because the index page-number is placed exactly on the page to which it corresponds; but 100
100 this index does not preclude anyone from also paging a book in addition with the

usual page-numbers placed in the upper corners or elsewhere of each page.

In large books containing, say, one thousand pages and over, where it might be inconvenient to arrange all the page-numbers, as described, the construction might be modified by indexing serial numbers only—thus, 5, 10, 15, 20, &c., as illustrated at B, Fig. 3—or by indexing in serial numbers of four pages only—thus, 4, 8, 12, 16, &c.—such a series, beginning with 120 and ending with 144, being indicated at E, Fig. 3, the latter method being the more preferable one for various obvious reasons; or I may arrange the book to be page-indexed into sections and index each section separately. For instance, supposing a book to contain one thousand pages, I arrange the first section so as to embrace the even numbers to 250 and the odd numbers from 251 to 499, and the second section to commence with 500 on the even series and end with 999 on the odd side of said index.

By using several sections in one book I am enabled to page-index the largest book now in practical use.

Instead of indexing the numbers so that the odd and even numbers are visible only, as heretofore described, I may arrange the tabs of the index so as to contain an odd and even number upon each, as shown at D, Figs. 1 and 2, thereby producing the correct numeration of all the numerals in the index. This may facilitate the finding of the odd pages in the first half of the book which has only even numbers, and the even pages on the second half, though for all practical purposes I consider the construction heretofore explained as ample and sufficient.

To readily open the book in the middle, to

expose the index or paging, I use a book-mark 40 preferably permanently affixed to the said book, though not necessarily so.

Having thus fully described my invention, I claim as new and desire to secure to me by Letters Patent of the United States— 45

1. A book having a page-index and page-number combined, substantially as described, the page-numbers of the even series being placed on one side and those of the odd series on the opposite side of the book, said numbers running along the edges of the leaves 50 from top to bottom in multiples of rows, the book being provided with a mark dividing the even and odd series, as and for the object stated.

2. A page-index for books to locate the pages, consisting, essentially, of two divisions, one having a series of even numbers placed upon the left-hand side and the other having the series of odd numbers on the right-hand 60 side, each page-number being placed upon a spot in its respective division other than the top corner of the page and the rest of said page in the index cut away below said numbers, whereby all the numbers in the divisions 65 are exposed to view simultaneously when the book is opened in the middle between the two divisions, said book being provided with a marker indicating the place where the two divisions separate, as and for the purpose 70 stated.

In testimony that I claim the foregoing as my invention I have hereto set my hand in the presence of two subscribing witnesses.

JOHN A. COOK.

Attest:

MICHAEL J. STARK,
J. H. MATTESON.
